[57] CLAIM

The ornamental design for a tire, substantially as shown
and described.

DESCRIPTION

FIG. 1 is a perspective view of a tire showing our new
design, it being understood that the tread pattern is
repeated throughout the circumference of the tire, as
shown schematically by solid lines, the opposite side
being substantially the same as that illustrated; and
FIG. 2 is a plan view of the tread of the tire of FIG. 1.
